CURTAIN HANGER

James Howard, Jr., Fairfield, and Albert C.
Noland, Pratt City, Ala.

Application July 9, 1945, Serial No. 603,847

3 Claims. (Cl. 160—339)

1

This invention relates to curtain or drape supporting means, and more particularly to an improved bracket structure by means of which heavy drapes or curtains may readily be mounted in and removed from the supporting brackets.

An object of this invention is to provide an improved curtain or drape hanger which includes a pair of supporting brackets having rod clamping clips which are directed downwardly and which are adapted to normally yieldably hold a curtain or drape rod therein. The brackets include elevating means which are connected to the curtain or drape rod by means of which the rod may be raised to clamping position so that the curtains or drapes may be secured in the supporting brackets without the use of a step ladder or other means.

A further object of this invention is to provide a curtain or drape supporting means which is so constructed that the curtain or drape may be lowered by merely releasing the elevating means and pulling the curtain or shade downwardly to disengage the rod from the yieldable clips or clamps.

With the foregoing objects in view, and others which may hereinafter more fully appear the invention consists of the novel construction, combination and arrangement of parts, as will be more specifically described, and illustrated in the accompanying drawings, wherein are shown embodiments of the invention, but it is to be understood that changes, variations and modifications may be resorted to which fall within the scope of the invention, as claimed.

In the drawings:

Figure 1 is a front elevation of a curtain supporting means constructed according to an embodiment of this invention.

Figure 2 is a fragmentary sectional view taken on the line 2—2 of Figure 1.

Figure 3 is a fragmentary front elevation, partly in section, on an enlarged scale, of one of the brackets.

Figure 4 is a sectional view taken on the line 4—4 of Figure 2.

Figure 5 is a fragmentary sectional view taken on the line 5—5 of Figure 2.

Referring to the drawings the numerals 10 and 11 designate generally a pair of brackets which are adapted to be secured to supporting frame members 12 and 13 respectively which may form part of a window or door opening. The two bracket members 10 and 11 are of like construction, and each includes a substantially U-shaped member 14 which has extending from the rear

2

open end thereof a pair of bifurcated arms 15 terminating in outwardly directed feet 16 which are secured by fastening members 17 to the supporting structures 12 and 13. The U-shaped member 14 has secured to the lower leg 18 thereof, a resilient clip 19 which is adapted to resiliently clamp one end of a curtain rod 20 therein. A curtain rod 20, preferably has mounted on each end thereof, a sleeve 21, which has secured to its outer end a decorative knob 22. The clip 19 is secured to the lower leg 18 of the U-shaped member 14 by means of a rivet or fastening member 23. The clip 19 opens downwardly and is formed with outwardly flared lower arms 24, by means of which the sleeve 22 may be readily moved upwardly to engagement with the clip 19 and the sleeve 22 may be forcibly pulled straight downwardly to release the sleeve 21 and the rod 20 from the clip.

20 In order to provide a means whereby the rod 20 may be either elevated or lowered, we have provided a grooved pulley 24, mounted on a shaft 25. The shaft 25 is carried by a U-shaped clamp member 26, which is formed with reverted ends 27. The U-shaped clamping member 26 engages over the parallel sides of the U-shaped member 14, and holds the arms or sides of the U-shaped member 14 against spreading.

An elongated cord or flexible member 28 is 30 trained about the pulley 24 and is secured to the head or decorative member 22 through a lug 29, carried by a head or decorative member 22. The opposite end of the flexible member 28 may be extended through one or more guide eyes 30 and may have a tassel 31 on the lower end thereof.

In the use and operation of this hanger structure the curtain C is looped or draped over a rod 20 between the ends 22 and between the sleeves 21. The rod 20 is initially disposed in a lowered position and after the curtain C is mounted on the rod 20, this rod is raised by pulling downwardly on the two flexible members 28 until the opposite ends of the rod 20 are clamped in the 45 clips or clamping members 19.

When it is desired to lower the rod and the entire curtain the curtain may be bodily pulled downwardly to release the ends of the rod 20 from the clips 19. It will be understood that the guide members 30 may be formed as a limiting means to limit the lowered position of the rod 20.

What we claim is:

1. A curtain hanger comprising a pair of 55 bracket members, a downwardly directed resili-

ent clip carried by each member, a curtain rod engageable with said clips, and means carried by said bracket members and connected to said rod for elevating or lowering said rod.

2. A curtain hanger comprising a pair of bracket members, a downwardly directed resilient rod supporting and clamping clip carried by each member, a rod engageable with said clips, a pulley carried by each member, and flexible members respectively engaging said pulleys and connected to ends of said rod whereby the latter may be elevated or lowered.

3. A curtain hanger comprising a pair of bracket members, each member being formed of a U-shaped outer part and a pair of di-

10
15

vergent arms extending from the free legs of said outer part, a downwardly directed resilient clip carried by the lower leg of each outer part, a rod engageable with said clips, a right angularly disposed U-shaped member carried by the legs of said outer part, opposed flanges carried by the legs of said U-shaped members for holding the latter on the legs of said outer part, a pulley, means engaging the bight of said U-shaped member rotatably supporting said pulley, and a cord trained over said pulley and secured to an end of said rod for elevating or lowering said rod.

JAMES HOWARD, JR.
ALBERT C. NOLAND.
